(57) **CLAIM**

The ornamental design for a bipod, as shown and described.

DESCRIPTION

FIG. 1 is a left, top, rear perspective view of a bipod showing our new design;

FIG. 2 is a rear elevation view of the bipod of FIG. 1;

FIG. 3 is a front elevation view of the bipod of FIG. 1;

FIG. 4 is a left side elevation view of the bipod of FIG. 1;

FIG. 5 is a right side elevation view of the bipod of FIG. 1;

FIG. 6 is a top view of the bipod of FIG. 1; and,

FIG. 7 is a bottom view of the bipod of FIG. 1.

The intermittent lines depict shading and contour.

The features drawn in broken line in all figures are portions of the bipod that form no part of the claimed design.
